United States Patent Office

Des. 196,387
Patented Sept. 24, 1963

196,387

CUTTING MACHINE

Richard C. Maxant, Ayer, Mass., assignor to Chandler
Machine Company, Ayer, Mass., a corporation of
Massachusetts

Filed Aug. 2, 1961, Ser. No. 66,164

Term of patent 14 years

(Cl. D55—1)

FIG. 1 is a perspective view of a cutting machine embodying my new design;

FIG. 2 is a plan view thereof;

FIG. 3 is a rear perspective view thereof; and

FIG. 4 is an end view thereof.

The dominant features of the design reside in the portions shown in full lines on the drawings.

I claim:

The ornamental design for a cutting machine, as shown and described.
